UNITED STATES PATENT OFFICE.

CHARLES S. HALL, OF NEWARK, NEW JERSEY, ASSIGNOR TO THE WHITEHEAD & HOAG CO., OF NEWARK, NEW JERSEY.

BANK.

Application filed May 28, 1919. Serial No. 300,373.

To all whom it may concern:

Be it known that I, CHARLES S. HALL, of Newark, in the county of Essex, in the State of New Jersey, have invented new and useful Improvements in Banks, of which the following, taken in connection with the accompanying drawings, is a full, clear, and exact description.

This invention relates to certain new and useful improvements in banks and pertains particularly to savings banks of the small portable type adapted to be carried in the individual's pocket and into which coins may readily be inserted and be withdrawn therefrom only upon opening the bank by the use of suitable key in the hands of someone familiar with the locking mechanism, this type of bank being commonly used by savings banks institutions for distribution among its customers as an advertising novelty.

The general object of the invention is to produce a savings bank of small size and of relatively simple and inexpensive construction and which will be highly efficient for the purpose designed.

Specific objects and advantages relate to and reside in the details of construction of the bank, with particular reference to the mechanism for removably locking the separable parts together, all of which will more fully appear from the following description taken in connection with the accompanying drawings in which—

Figure 1 is a perspective view of a bank of this invention.

Figure 2 is a horizontal cross section of the same showing the separable parts locked together.

Figure 3 is a view similar to Figure 2 showing the separable parts unlocked.

Figure 4 is a cross section on line 4—4, Fig. 2.

Figure 5 is a cross section on line 5—5,

Fig. 2.

Figure 6 is a perspective view of key adapted for use in connection with the bank.

The invention as shown comprises a substantially cylindrical side-wall —1— having its upper edge formed with an enlarged part or parts —2— for retaining a cap ring —3—, which ring is adapted in turn to be interlocked with and retained by a flanged

cap —4— and preferably as shown the cap —4— is provided with a covering —5— of suitable material as celluloid or the like for receiving or displaying advertising or other matter and in the specific illustration the edge of the celluloid sheet —5— is wrapped about the flanged edge of cap —4— and is confined between the said flanged edge —6— and the cap ring —3—. The parts so far described are in the manner shown permanently secured together and constitute an inverted cup shaped structure.

The lower edge of the side wall —1— is provided with an inturned circumferential flange —7— formed with a series of openings —8—, in this particular illustration four equally spaced openings being shown, to permit the passage of four equally spaced lugs —9— struck up from a base cap —10— having its marginal portion formed with a flange —11— adapted for securing to a base ring —12— having an internal diameter substantially equal to the external diameter of the body —1— so as to freely slide thereover in assembling and disassembling the base cap and the body of the bank. Preferably this base cap in like manner as the cap —4— is provided with a covering of suitable material such as celluloid or the like for receiving or displaying advertising or other matter and as illustrated the edge of the celluloid sheet —13— is wrapped about the flange —11— and is confined between said flange and the base ring —12—. The base cap —10—, the base ring —12— and the celluloid sheet —13— constitute a permanently associated structure.

The lugs —9— preferably comprise a vertical portion —14— of a length somewhat greater than the thickness of the flange —7— and a horizontal portion —15— of a length substantially equal to the radial width of slots —8— and for the purpose of locking the base cap —10— to the flange —8— a rotatable annular ring or wheel —16— is provided preferably permanently secured to the flange —7— in a manner to permit relative rotary movement of the parts and this may be effected by forming the flange —7— with a circumferential head —17— bent around the inner edge of the wheel —16—. The wheel —16— has its periphery formed with step portions, there being preferably three

steps corresponding to each lug —9—. The inner step —18— when aligned with an opening —8— permitting free passage of the lug —9— through said opening. The second step —19— extending some distance radially and outwardly from the periphery of step —18— so as to partially close an opening —8— when in registration therewith and of a thickness to freely slide beneath the horizontal portion —15— of a lug —9— to lock the lug against removal through the said opening. The third step —20— extends still farther radially and outwardly than the step —19— and constitutes a limiting stop when brought into contact with a lug —9— to prevent further revolution of wheel —16—.

The operation of assembling the device will be readily understood. When the parts are separated, the step —18— should lie adjacent the opening —8— so as not to obstruct the said opening. Respective lugs —9— may then be passed through openings —8— and the wheel —16— rotated to bring the projections or steps —19— beneath respective lugs —9— to lock the lugs against removal through said openings. The unlocking of the parts is effected by a reverse rotation of wheel or locking ring —16—. For the purpose of facilitating this locking and unlocking process the wheel —16— is provided with a peripheral recess —21— of a size adapted to receive a projection —22— upon a key —23—. The end part —24— of the key may be passed through the coin slot —25— and the flange —22— brought into the recess —21— and by movement of the handle of the key proper rotary movement of the wheel may be effected to either lock or unlock the separable parts. Preferably the coin slot —25— is normally covered by flexible curtain —26— which may be supported in any suitable manner as by frictional engagement between the body —1— and flange —27— formed thereon and reversely bent to contact with the inner wall of the curtain.

Although I have described the complete bank structure embodying specific details of form, shape and arrangement, I do not desire to limit myself to the same, as the features of this invention relate to the mechanism for securing the separable parts together and said mechanism may be utilized in connection with various and modified structures and may itself be varied and modified in details without departing from the spirit of this invention as set forth in the appended claims.

60 10 What I claim is:

1. A bank comprising a substantially cup shaped body, a cap closing the open end of the body and means rotatably carried by the body for locking the cap to the body.
- 65 2. A bank comprising a substantially cup

shaped body, a cap and means carried by the body and rotatable with reference thereto for locking the body to the cap.

3. A bank comprising a substantially cup shaped body having an inturned flange at its open end, a cap and rotatable means for securing the cap to said flange.

4. A device of the class described, comprising a substantially cup-shaped body, a cap for closing the open end of said body, and a device carried by one of said members and rotatable with respect to both of the members for securing the body and cap together.

5. A bank comprising a substantially cup-shape body having an inturned flange at its open end provided with a plurality of openings, a cap closing said open end and having a series of lugs passed through said openings and a rotatable wheel movable into engagement with said lugs to lock the body and the cap.

6. A bank comprising a substantially cup-shape body having an inturned flange at its open end provided with a plurality of openings, a cap closing said open end and having a series of lugs passed through said openings, a rotatable wheel movable into engagement with said lugs to lock the body and the cap, and means for limiting the rotation of said wheel when the parts are locked.

7. A bank comprising a substantially cup-shape body having an inturned flange provided with a plurality of openings, a locking wheel rotatably secured to said flange at its open end, a cap closing said open end and having a plurality of lugs passed through respective openings when said locking wheel is in a predetermined position, said wheel upon rotary movement engaging said lugs to prevent their removal through said opening.

8. The combination with a bank formed of a substantially cup-shape body and a cap closing the open end thereof, said body having a normally opened coin slot, of a rotatable member carried by one of said parts and adapted to engage the other part to lock the separable parts together, said rotatable member having a key seat and a key insertable through said coin slot for engaging the key seat to effect rotation of said member.

9. A bank comprising a substantially cup shaped body having an inturned flange at its open end, a cap positioned upon the outer side of said flange and having lugs adapted to lie upon the inner side of said flange and means movable between the flange and the said lugs for locking the cap to the body.

10. A bank comprising a body and a cap closing the open end thereof and rotary locking means rotatably carried by one of said members and adapted to engage between the flange and the said lugs for locking the cap to the body.

parts of said members to lock them in assembled position.

11. A bank comprising a substantially cup shaped body and a cap closing the open end thereof and means carried by one of said members and rotatable with respect to both members for interengaging between a plurality of respective parts of said members

to lock the members in assembled position.
In witness whereof I have hereunto set 10
my hand this 14th day of May 1919.

CHARLES S. HALL.
